CARBURETOR

Elmer M. Bimberg, Detroit, Mich., assignor to Bendix Aviation Corporation, South Bend, Ind., a corporation of Delaware

Application August 13, 1948, Serial No. 44,183

9 Claims. (Cl. 137—434)

The present invention relates to carburetors and more particularly to a fuel inlet valve control mechanism for carburetors.

One of the principal objects of the present invention is to provide a simple and positive connection between the float lever and fuel inlet valve of a carburetor in which there is no appreciable backlash or lost motion and which permits the float and valve to be readily assembled in the carburetor and thereafter easily serviced.

Another object of the invention is to provide a readily responsive fuel inlet valve control mechanism for a carburetor adapted to minimize the effect of engine vibration and road jarring on the operation of the fuel inlet valve.

Further objects and advantages of the present invention will become apparent from the following description and accompanying drawings, wherein:

Figure 1 is a side elevation of a carburetor embodying my invention in which the fuel bowl and valve are shown in cross-section;

Figure 2 is a view of the float and fuel valve of Figure 1 removed from the carburetor;

Figure 3 is a top plan view of a modified form of my invention showing the connection between the float lever and fuel valve in section;

Figure 4 is a view of the float lever, fuel valve connection taken on line 4—4 of Figure 3; and

Figure 5 is a fragmentary side elevation of the float and fuel valve shown in Figure 3.

Referring more specifically to the drawings, numeral 10 designates an air horn of a single barrel downdraft carburetor, numeral 12 a fuel bowl mounted on and formed integrally with the main body of the carburetor, and 14 a throttle valve mounted on a shaft 16 in throttle body 18, a flange 20 being provided at the base of the throttle body for securing the throttle body to an intake manifold (not shown). The fuel is delivered to the fuel bowl from a suitable source, such as a tank or fuel pump, through a conduit 26 to a fuel inlet valve 28. The valve is controlled by a float 30 supported by a lever 32 pivoted on a pin 34 at a point between the float and fuel inlet valve. In the embodiment of the invention shown in Figures 1 and 2, ears 40 and 42 formed integrally with the float lever on the end opposite the float are turned downwardly and inwardly to form an open ring-shaped member, as clearly shown in the end view of Figure 2. When the fuel valve and float are assembled, the head 44 on valve 28 is placed in the ring, and the neck connecting the head and the body portion 46 of the valve is interposed between the two free ends of ears 40 and 42. In place of the annular groove forming the neck of the valve, a shoulder or rib may be formed on the surface of the valve near the end thereof. When used hereinafter, the word "shoulder" will include an annular rib, one side of an annular groove or the underside of a head such as head 44.

After the head has been inserted in the ring, the ends of the ears may be pressed inwardly against the underside thereof to eliminate substantially all play from the connection so that there will be no backlash or lost motion between the float lever and fuel valve during operation of the float mechanism. In the embodiment shown in Figure 1, as the quantity of fuel in the fuel bowl decreases, the float is adapted to positively lift the fuel valve from its seat without having to depend on the fuel supply pressure to unseat the valve.

In the embodiment shown in Figures 3, 4 and 5, the

ears 40 and 42 are stamped or otherwise severed from the float lever on three sides, leaving the ears integrally connected to the lever on the fourth side near the outside edge of the lever. A bar 48 is left between the two ears. The ears are bent downwardly to provide a triangularly-shaped support into which the head of the fuel valve is inserted. The ends of ears 40 and 42 fit snugly under the head 44 of the valve, holding the fuel valve in close relationship to the float lever so that no appreciable play exists in the connection. The principal advantage of this arrangement over the first embodiment is that this arrangement may be fabricated with fewer operations.

Although Figure 5 illustrates the modified form of a float lever, fuel valve connection, this figure also shows a horizontal fuel inlet valve and a modified form of float lever. This valve and float lever arrangement may be used equally as well in the embodiment of Figures 1 and 2. Further arrangements and modifications may be made in the present float mechanism without departing from the scope of the invention.

I claim:

1. In a fuel control mechanism for a float type carburetor, comprising a fuel inlet valve having an annular shoulder, a float, a lever joined to said float having a longitudinal center portion for engaging one end of said valve and having ears extending from each side thereof forming an open ring-shaped member, the ends of said ears being disposed adjacent said shoulder on opposite sides of said valve and adapted to hold said valve end in contact with said center portion.

2. In a fuel control mechanism for a float type carburetor comprising a fuel inlet valve having an annular groove near the end opposite the valve seat, a float, a pivoted lever joined to said float having a longitudinal center portion for engaging one end of said valve and having ears of resilient material extending outwardly from each side of said lever, each of said ears being bent in a smooth curve extending below the plane of said lever to extend toward each other in alignment with each other, the free ends of said ears being disposed in said groove on opposite sides of said valve and adapted to hold said valve end in contact with said center portion.

3. A fuel inlet control mechanism for a float type carburetor comprising a fuel inlet valve having an annular shoulder near one end thereof, a lever having a longitudinal center portion for engaging one end of said valve, a float secured to one end of said lever, and a pair of ears joined to opposite outside edges of said lever near the other end thereof, the free ends of said ears being adapted to embrace said shoulder on opposite sides of said valve and adapted to hold said valve end in contact with said center portion.

4. A fuel inlet control mechanism for a carburetor comprising a fuel inlet valve having an annular groove near one end thereof, a float, a lever joined to said float and having a longitudinal center portion for engaging one end of said valve, ears extending outwardly from each side of said lever and bent in a smooth curve extending below the plane of said lever to extend toward each other, the ends of said ears being adapted to extend into said groove on opposite sides of said valve and adapted to hold said valve end in contact with said center portion, and a pivot for said lever between said float and said ears.

5. A control mechanism for a fuel valve having an annular shoulder thereon comprising a lever having a longitudinal center portion for engaging one end of said valve, a float secured to said lever, and a pair of resilient ears joined to said lever on opposite outside edges thereof and spaced from said float, said ears extending from said lever toward one another and being adapted to engage said shoulder on opposite sides of said valve to hold said valve end in contact with said center portion.

6. A control means for a fuel inlet valve having an annular shoulder thereon comprising a flat sheet metal lever, a valve engaging means on said lever including a center member for engaging the end of said valve, a slot on each side of said member, and deformable clamping elements adjacent said slot adapted to engage said annular shoulder and to be pressed firmly against said shoulder.

whereby a snug fit is obtained between said valve and said lever.

7. A control means for a fuel inlet valve having an annular shoulder thereon comprising a lever of flat sheet metal material, a longitudinal center member adjacent one end of the lever for engaging the end of said valve, a slot on each side of said member, and a clamping element joined to said lever along each side thereof adjacent said slots and extending inwardly for engaging said annular shoulder.

8. A control means for a fuel inlet valve having an annular shoulder thereon comprising a flat sheet metal lever, a longitudinal member in the center of said lever for engaging the end of said valve, a slot on each side of said member, a longitudinal member along each side of said lever adjacent said slots, and a valve engaging element extending inwardly at an angle to said lever from the inside edge of each of said side members.

9. A control means for a fuel inlet valve having an annular shoulder thereon comprising a pivoted lever of sheet metal material, a longitudinal member in the center of said lever for engaging the end of said valve, a slot on each side of said member, a longitudinal member adjacent said slots along each side of said lever, and an

element resiliently secured to and extending inwardly at an angle to said lever from the inside edge of each of said members for engaging the shoulder on said valve.
